TWO PASSENGER BUCKBOARD MOTOR VEHICLE

Levitt Luzern Custer, Dayton, Ohio

Application December 18, 1958, Serial No. 53,814

Term of patent 14 years

(Cl. D14—3)

FIG.1

FIG.2

FIG.3

FIG.4

Figure 1 is a side elevational view of a two passenger buckboard motor vehicle, embodying my new design, the opposite side being substantially the same.

Figure 2 is a top plan view;

Figure 3 is a front end view on a reduced scale; and

Figure 4 is a rear end view thereof.

I claim:

The ornamental design for a two passenger buckboard motor vehicle, as shown and described.
